187,573

NASAL SPRAY INHALER

Philip H. Sagarin, Bridgeport, Conn., assignor to Valve Corporation Of America, Incorporated, Bridgeport, Conn., a corporation of Connecticut

Application December 30, 1957, Serial No. 49,066

Term of patent 14 years

(Cl. D83—1)

Fig. 1.

Fig. 2.

Fig. 3.

Fig. 4.

Fig. 5.

Figure 1 is a front perspective view of a nasal spray inhaler showing my new design;

Figure 2 is a rear perspective view thereof;

Figure 3 is a top plan view of Fig. 1 on a reduced scale, rotated approximately 90°;

Figure 4 is a side elevational view of Fig. 3; and Fig. 5 is a longitudinal cross sectional view of Fig. 4. I claim:

The ornamental design for nasal spray inhaler, as shown.
